ENGINE STARTER

Application filed May 29, 1928. Serial No. 281,527.

This invention relates to starters for internal combustion engines and more particularly to the "follow-up" type of starter in which the pinion, when driven by the engine, overruns its driving means until it is demeshed by the operator and the object of the present invention is to provide a starter of this type which will operate efficiently, overrun quietly and indefinitely without damaging its parts and will reset quickly.

We attain our objects by means of the constructions briefly described as follows. On an axially movable member, which may be the armature shaft of the starter motor or a member splined on the shaft, is mounted a sleeve or intermediate driving member which has an overrunning or one way clutch connection with the pinion. The latter is journalled on the shaft and means is provided to limit the axial movement in one direction of the pinion relative to the first mentioned member. A collar having a limited sliding engagement with the sleeve or intermediate driving member frictionally engages a flange on the pinion whereby when the first member overruns the pinion the sleeve will be caused to move along its thread towards the pinion to set the clutch, and when the pinion overruns the first member, the sleeve will be caused to move away from the pinion to unset the clutch. A manually operable lever is adapted to move the first named member axially and is adapted to actuate a switch to energize the starter motor. A continuous movement of the lever will move the device as a whole towards the gear of the engine to be started and into mesh therewith if the teeth on the pinion are in alinement with the spaces between the teeth on the gear.

If the pinion teeth collide with the gear teeth, the first member will move relative to the sleeve or intermediate driving member and these members have a threaded connection, whereby the intermediate driving member will be rotated to turn the pinion sufficiently to clear its teeth and then be axially moved to mesh the pinion.

When the engine starts the pinion will overrun the sleeve or intermediate driving member and the collar will effect and main-

tain a separation of the clutch parts during such overrunning thereof. The collar will also reset the clutch parts when the sleeve overruns the pinion.

We attain our object by the constructions hereinafter more fully described and illustrated in the accompanying drawings in which

Fig. 1 is a longitudinal section, partly in side elevation, of our starter showing the parts with the clutch in driving position;

Fig. 2 a sectional detail, partly in side elevation, of some of the parts shown in Fig. 1, showing them as they are positioned while the pinion is about to be turned to clear its teeth;

Fig. 3 a sectional detail, partly in side elevation, showing the parts as they are positioned when the pinion is driven by the engine;

Fig. 4 a longitudinal section of a modified form of our starter showing the parts with the clutch in driving position;

Fig. 5 a sectional detail partly in side elevation showing the parts in Fig. 4 as they are positioned when the pinion is driven by the engine; and

Fig. 6 a sectional detail showing the preferred construction of the extension, and pinion and flange assembly in connection with a starter of the jump spring type, the parts being shown as they are positioned when the pinion is driven by the engine.

In the drawings like numerals of reference indicate corresponding parts in the different figures.

Referring to Figs. 1, 2 and 3, 1 is an electric motor provided with an extended armature shaft 2. A member 3 straight splined at 4 on the shaft has a driving threaded connection 5 with a sleeve or intermediate driving member 6. The latter is disposed on the member 3 and is provided with ratchet teeth 7 for engaging ratchet teeth 8 carried by a pinion 9 and which may be the ends of the teeth thereof. The pinion is journalled on the shaft 2. The teeth 7 on the sleeve 6 and the teeth 8 carried by the pinion 9 are shaped to form a one way clutch or driving connection between the sleeve and the pinion.

The axial movement in one direction of the pinion relative to the member 3 is limited by means of a cup shaped extension 10 secured to the said member. Rigidly attached to the 5 forward end of the extension is a ring 11 which forms a shoulder for engaging the forward side of a flange 12 which is suitably secured to the pinion. We may in some cases use a spring 13 to urge the sleeve 6 towards 10 the pinion and thus tend to engage ratchet teeth 7 and 8 but this spring is in no way essential to the operation of the device.

A lever 14 suitably connected with any manually operable means such as a foot pedal 15 (not shown) is adapted to engage the walls of a groove 15 formed at the rear end of the extension 10 whereby the latter and the member 3 may be axially moved with or relative to the sleeve 6 and pinion 9.

20 The operation is as follows, spring 13 being considered omitted by moving the upper end of the lever to the left, the lower end thereof, the extension 10, member 3 and sleeve 6 will be moved to the right, teeth 7 will contact with 25 teeth 8 and pinion 9 will be moved towards the flywheel gear 16. If the spaces between the teeth of the latter be in alinement with the teeth of the pinion, the latter will be moved into mesh with the gear. If the teeth 30 of the pinion collide with the teeth of the gear the axial movement of the pinion and sleeve 6 will be stopped with the clutch teeth 7, 8 in contact. The continued movement of the member 3 will urge, by means of the 35 thread 5, the sleeve 6 and pinion 9 to the right and the thread 5 passing through the sleeve 6 will turn it and thus the pinion until its teeth clear the gear teeth. A further movement of the member 3 will move the sleeve and pinion so that the latter meshes with the gear 40 16. After the lever 14 has moved the member 3 to mesh the pinion it engages a switch 17 to energize the starter motor 1 which will turn the member 3 to move the sleeve and pinion axially by means of the thread 5 until 45 flange 12 engages the ring 11 in which position the pinion is fully meshed with the gear. The starter motor will now turn gear 16 to start the engine.

50 When the engine fires the gear 16 will rotate the pinion 9 faster than the motor 1 is driving it whereby the flange 12 on the pinion will tend to overrun a collar 18 which has a straight or helical spline connection 20 with the sleeve 6. The collar 18 is kept in constant frictional contact with the flange 12 by any suitable means such as a spring 19. The frictional drag between the collar 18 and the flange 12 will cause the collar to turn with 55 the flange which will result in the sleeve 6 being wormed along its thread 5 to the left and away from the pinion 9 to unset the clutch 7, 8 and to hold it unset. While the pinion is in mesh with the gear and the engine is running, the flange 12 and the collar 18

will be moving in the same direction of rotation but at very different speeds which might result in their contacting surfaces being damaged. This is prevented by the engagement of a flange 21 on the sleeve 6 with the collar 18. When the sleeve 6 travels to the left it passes through the collar 18 until the flange 21 engages the right hand side of the collar which limits the axial movement in this direction of the sleeve 6. This engagement of the flange 21 with the collar 18 also urges the latter away from the flange 12 to lessen the frictional drag between the flange 12 and collar, which results in a light but always sufficient friction between the said flange and collar so that their contacting surfaces will last indefinitely.

70 The flange 21 is adapted to position the teeth 7 on sleeve 6 with regard to the teeth 8 on the pinion 9 so that when they are in their unset position they will have a constant minimum clearance which is very important to eliminate jar on resetting as hereinafter described. As heretofore set forth, one of the 75 functions of the collar 18 is to hold the clutch unset while the pinion 9 is overrunning the sleeve 6 which prevents objectionable noise or damage by the teeth 7 if they should drift into contact with the teeth 8 but an equally important function of the collar 18 is that it 80 resets the clutch immediately the sleeve 6 overruns the pinion 9. When the speed of the pinion falls below that of the sleeve, and thus the speed of the flange 12 below that of the collar 18, the latter moves relative to the 85 sleeve to worm it to the right towards the pinion and thus reset the clutch teeth 7, 8. From this description it is obvious that the 90 driving connection between the shaft 2 and the pinion 9 will be re-established if the engine 95 dies down after firing.

100 It will be noted that the clutch is entirely under the control of the flange 12, collar 18, thread 20, sleeve 6 and thread 5. It may, however, in some cases be advisable to use the 105 spring 13 which tends to move the sleeve 6 axially to the right and thus take up any backlash between the parts of the threaded connections 20 and 5. When this spring is 110 employed the action is the same but the setting of the clutch may be a little quicker and slightly more frictional force may be necessary to keep the teeth 7, 8 separated during the overrunning of the pinion.

115 It is obvious that the above described collar 18 if threaded at 20^b on the sleeve 6^b would move the latter to clear the teeth 8^b and hold them from contacting with the teeth 7^b during the overrunning of the pinion in a 120 jump spring type of starter as shown in Fig. 6. In this type of starter the driving connections 5^b would be formed as straight or very long pitched splines and the pinion 125 would be rotated, by energizing the motor, to clear the pinion teeth if they collided with 130

the gear teeth. In Fig. 6 the flange 12^c on the pinion 9^b is provided with ratchet teeth 8^b whereby the thrust, if the spline 5^b be helical, is taken by the flange which bears against

- 5 the ring 11^b on the member 10^b. In other words, equal pressure is applied to the opposite sides of the flange 12^c, which construction differs from that shown in Figs. 1, 2 and 3 in which the thread thrust tends to dislodge 10 the flange 12^c. If the spline 5^b be straight the setting and unsetting of the clutch 7^b, 8^b is effected by the thread 20^b.

Referring to the modification shown in Figs. 4 and 5, the armature windings 22 of the starting motor 1^a are carried on a core 23 which is feather-keyed on the armature shaft or member 2^a whereby the latter may be axially moved to serve both as the shaft 2 and member 3 of the construction shown in 20 Figs. 1 to 3. To the shaft or member 2^a is secured a shifter ring 10^a having a groove 15^a for receiving the forked ends of a lever 14^a. A sleeve or intermediate driving member 6^a is threaded on the threads 5^a and is provided 25 with a frusto-conical surface 7^a adapted to cooperate with a surface 8^a formed on a cup-shaped flange 12^a. This flange is carried by a pinion 9^a which is journaled on the shaft 2^a and the surfaces 7^a and 8^a form a friction 30 cone clutch between the sleeve 6^a and pinion 9^a.

A thrust collar 11^a suitably secured to the shaft forms an abutment to limit the axial movement in one direction of the pinion relative to the shaft. A collar 18^a splined on the sleeve 6^a has a frictional contact, by any suitable means such as a spring 19^a, with the rear surface 12^a of the pinion flange 12^a.

A movement to the right of the lower end 40 of the lever 14^a will move the shifter ring 10^a, shaft 2^a, sleeve 6^a, abutment 11^a, spring 19^a, collar 18^a and pinion 9^a as a whole towards the flywheel gear 16^a and will mesh the pinion with the gear if the teeth of the pinion be in alignment with the spaces between the teeth of the gear.

Should the pinion teeth collide with the gear teeth, the axial movement of the pinion 9^a, sleeve 6^a, and collar 18^a will be stopped 50 and the shaft 2^a will be moved relative thereto to cause the pinion to be rotated sufficiently to clear its teeth in a manner similar to any one of those described for the ratchet type of clutch.

When the engine fires the clutch is disengaged by the pinion 9^a which overruns the shaft 2^a and thus causes the sleeve 6^a to overrun the threads 5^a whereby the sleeve is 60 axially moved away from the pinion. This axial movement of the sleeve is continued by means of the friction drag between the collar 18^a and surface 12^a on the pinion flange 12^a which tends to turn the sleeve with the pinion until the shoulder 21^a is moved into 65 engagement with the collar to relieve the

friction between the collar 18^a and the surface 12^a. The overrunning wear, it will be noted, is on the collar 18^a and surface 12^a and not on the clutch surfaces 7^a, 8^a.

In this construction the collar 18^a causes 70 the resetting of the clutch, when the speed of the pinion falls below that the sleeve 6^a, in the same manner as that described for the ratchet type clutch. A spring 13^a may be employed with this cone type of clutch to 75 take up any backlash in the threaded connections 20^a and 5^a.

When the engine commences to fire regularly the operator permits a spring 25, 25^a to return the parts to their normal position 80 in which the clutch 7, 8, 7^a, 8^a is unset.

What we claim is:

1. An engine starter including a longitudinally movable rotatable member; a sleeve having a threaded connection with the member; a starter pinion adapted to be moved axially to mesh with a gear of an engine to be started; and normally operative drive connecting means including a spring actuated toothed clutch between the sleeve and pinion adapted to permit the pinion to overrun the sleeve, the member when moved axially being adapted to mesh the pinion with the gear and to cause the said sleeve to rotate the pinion to clear its teeth if they should collide with the teeth of the gear. 90

2. An engine starter including a rotatable shaft; a starter pinion journaled on the shaft and adapted to be moved axially to mesh with a gear of an engine to be started; 100 a member having a drive connection with the shaft and axially movable thereof; a sleeve having a threaded connection with the member; and normally operative drive connecting means including a spring actuated clutch between the sleeve and pinion adapted to permit the pinion to overrun the sleeve, the member when moved axially being adapted to mesh the pinion with the gear and to cause the said sleeve to rotate the pinion to 110 clear its teeth if they should collide with the teeth of the gear.

3. An engine starter including a longitudinally movable rotatable member; a sleeve having a threaded connection with the member; 115 a starter pinion adapted to be moved axially to mesh with a gear of an engine to be started; drive connecting means including a spring actuated clutch between the sleeve and pinion adapted to permit the pinion to overrun the sleeve; means for axially moving the member to mesh the pinion with the gear and to cause the said sleeve to rotate the pinion to clear its teeth if they should collide with the teeth of the gear; and means 120 for effecting a separation of the drive connecting means during such times as the pinion overruns the sleeve.

4. An engine starter including a longitudinally movable rotatable member; a sleeve 130

having a thread connection with the member; a starter pinion adapted to be moved axially to mesh with a gear of an engine to be started; drive connecting means between the sleeve and pinion adapted to permit the pinion to overrun the sleeve; a spring tending to set the drive connecting means; means for axially moving the member to mesh the pinion with the gear and to cause the said sleeve to rotate the pinion to clear its teeth if they should collide with the teeth of the gear; and means operable by the pinion for disengaging the drive connecting means during such times as the pinion overruns the sleeve, the said disengaging means being adapted to move the sleeve to re-set the drive connecting means when the speed of the pinion falls below that of the sleeve.

5. An engine starter including a longitudinally movable rotatable member; a sleeve having a threaded connection with the member; a starter pinion adapted to be moved axially to mesh with a gear of an engine to be started; drive connecting means between the sleeve and pinion adapted to permit the pinion to overrun the sleeve; a spring tending to set the drive connecting means; means for axially moving the member to mesh the pinion with the gear and to cause the said sleeve to rotate the pinion to clear its teeth if they should collide with the teeth of the gear; and means separate from the drive connecting means and having a drive connection with the pinion adapted to permit slippage for effecting an axial movement of the sleeve away from the pinion when the latter overruns the sleeve.

6. An engine starter including a longitudinally movable rotatable member; a sleeve having a threaded connection with the member; a starter pinion adapted to be moved axially to mesh with a gear of an engine to be started; means for limiting the axial movement in one direction of the pinion relative to the member; drive connecting means between the sleeve and pinion and adapted to permit the pinion to overrun the sleeve; a spring tending to set the drive connecting means; means for axially moving the member to mesh the pinion with the gear and to cause the said sleeve to rotate the pinion to clear its teeth if they should collide with the teeth of the gear; a collar having a threaded connection with the sleeve, and a spring tending to move the collar to frictionally rotate with the pinion the two aforesaid threaded connections being inclined in opposite directions to the axis of the sleeve whereby the rotation of the collar relative to the sleeve will cause the latter to be axially moved away from the pinion during such times as the pinion overruns the sleeve.

7. An engine starter including a rotatable shaft; a starter pinion journalled on the shaft and adapted to be moved axially to mesh with

a gear of an engine to be started; a member having a drive connection with the shaft and axially movable thereof; a sleeve having a threaded connection with the member; means for limiting the axial movement in one direction of the pinion relative to the member; drive connecting means between the sleeve and pinion and adapted to permit the pinion to overrun the sleeve; a spring tending to set the drive connecting means; a flange on the pinion; a collar having a threaded connection with the sleeve; a spring tending to frictionally engage the collar with the flange, the two aforesaid threaded connections being inclined in opposite directions to the axis of the sleeve whereby the rotation of the collar relative to the sleeve will cause the latter to be axially moved away from the pinion during such times as the pinion overruns the sleeve.

8. An engine strater including a longitudinally movable rotatable member; a sleeve having a threaded connection with the member; a starter pinion adapted to be moved axially to mesh with a gear of an engine to be started; means for limiting the axial movement in one direction of the pinion relative to the member; drive connecting means between the sleeve and pinion and adapted to permit the pinion to overrun the sleeve; a spring tending to set the drive connecting means; means for axially moving the member to mesh the pinion with the gear and to move the member through the said sleeve to cause it to rotate the pinion to clear its teeth if they should collide with the teeth of the gear; a collar adapted to frictionally engage the pinion and having a splined connection with the sleeve and a spring tending to move the collar to frictionally rotate with the pinion, whereby the rotation of the collar by the pinion relative to the sleeve will cause the splined connection to turn the sleeve along its thread away from the pinion during such times as the pinion overruns the sleeve.

9. A starter comprising a pinion to be moved into and out of engagement with a gear of an engine to be started; a rotatable starter member axially movable and adapted to impart axial movement to the pinion to withdraw it from mesh; a sleeve threaded on the rotatable member having a direct disengageable driving connection with the pinion; a spring tending to set the drive connection; and frictional driving means between the pinion and the sleeve, the said means including a flange on the pinion, a collar having a sliding engagement with the sleeve, and a spring tending to press the collar against the flange, whereby relative rotary movement of the pinion and starter member will cause a relative rotation of the sleeve and said member and thus move the sleeve into and out of driving connection with the pinion.

10. An engine starter including a rotatable shaft; a starter pinion journalled on the shaft

and adapted to be moved axially to mesh with a gear of an engine to be started; a member having a drive connection with the shaft and axially movable thereof; a sleeve threaded on

- 5 the member; a clutch for connecting the said sleeve and pinion; a flange carried by the pinion; an extension carried by the member for engaging the forward side of the flange to limit the axial movement of the pinion in
 10 one direction; a spring engaging the extension and the sleeve to normally set the clutch; a collar threaded on the sleeve and having a frictional engagement with the rear side of the flange, the said two threads being directed
 15 oppositely to one another; and a spring engaging the extension and collar to hold the latter in frictional contact with the rear side of the flange whereby the latter will turn the collar relative to the sleeve to disengage the
 20 clutch during such times as the pinion overruns the sleeve.

11. An engine starter including a rotatable shaft; a starter pinion journaled on the shaft and adapted to be moved axially to mesh with

- 25 a gear of an engine to be started; a member having a drive connection with the shaft and axially movable thereof; a sleeve threaded on the member; a clutch for connecting the said sleeve and pinion; a flange carried by the pinion; an extension carried by the member for engaging the forward side of the flange to limit the axial movement of the pinion in one direction; a spring engaging
 30 the extension and the sleeve to normally set the clutch; a collar threaded on the sleeve and having a frictional engagement with the rear side of the flange, the said two threads being directed oppositely to one another; a spring engaging the extension and collar to hold the latter in frictional contact with the rear side of the flange whereby the latter will turn the collar relative to the sleeve to disengage the clutch during such times as the pinion overruns the sleeve; and a shoulder
 35 on the sleeve normally spaced from the collar and adapted to engage the latter to limit the axial movement of the sleeve when it is moved to disengage the clutch.

12. An engine starter including a longitudinally movable rotatable member; a pinion adapted to mesh with a gear of an engine;

- 40 an intermediate driving member; a one-way clutch between the pinion and intermediate driving member; a spring tending to set the clutch; and a helically splined driving connection between the first named member and intermediate member adapted to permit relative longitudinal movement between said members and to cause the intermediate member to turn the pinion to clear its teeth if they should collide with the teeth of the gear.

13. An engine starter including a longitudinally movable rotatable member; a pinion adapted to mesh with a gear of an engine; an intermediate driving member;

spring actuated clutch between the pinion and intermediate driving member; a helically splined driving connection between the said two members adapted to permit relative longitudinal movement between said members and to cause the intermediate member to turn the pinion to clear its teeth if they should collide with the teeth of the gear; and means for effecting a separation of the clutch during such times as the pinion overruns the intermediate driving member.

14. An engine starter including a longitudinally movable rotatable member; a pinion adapted to mesh with a gear of an engine; an intermediate driving member; a clutch between the pinion and intermediate driving member; a helically splined driving connection between the said two members adapted to permit relative longitudinal movement between said members and to cause the intermediate member to turn the pinion to clear its teeth if they should collide with the teeth of the gear; and means having a frictional driving connection with one of the said pinion and intermediate driving member parts and a driving connection with the other of said parts for effecting a separation of the clutch during such times as the pinion overruns the intermediate driving member and for effecting a driving engagement of the clutch when the speed of the pinion falls below that of the intermediate member.

15. An engine starter including a longitudinally movable rotatable member; a pinion adapted to mesh with a gear of an engine; an intermediate driving member; a one-way clutch between the pinion and intermediate driving member; a helically splined driving connection between the first named member and intermediate member adapted to permit the first named member to move longitudinally relative to the intermediate member to cause the latter to turn the pinion to clear its teeth if they should collide with the teeth of the gear; and a spring for causing the intermediate member to move relative to the first named member when the pinion teeth clear the gear teeth, the one-way clutch permitting this movement, thus preventing turning torque being applied to the pinion.

16. An engine starter including a longitudinally movable rotatable member; a pinion adapted to mesh with a gear of an engine; an intermediate driving member having a slideable driving connection with the first named member; a clutch between the pinion and intermediate driving member; and means for effecting a separation of the clutch during such times as the pinion overruns the intermediate driving member, the said means including a collar adapted to frictionally rotate with the pinion and having a slideable driving connection with the intermediate driving member, one of the said driving connections including a curved spline.

17. An engine starter including a longitudinally movable rotatable member; a sleeve having a threaded connection with the member; a starter pinion adapted to be moved axially to mesh with a gear of an engine to be started; a one-way tooth clutch between the sleeve and pinion adapted to permit the pinion to overrun the sleeve; means for axially moving the member to mesh the pinion with the gear and to cause the said sleeve to rotate the pinion to clear its teeth if they should collide with the teeth of the gear; and means for effecting and maintaining a separation of the toothed clutch during such times as the pinion overruns the sleeve.
18. A starter comprising a pinion to be moved into and out of engagement with a gear of an engine to be started; a rotatable starter member axially movable and adapted to impart axial movement to the pinion to withdraw it from mesh; a sleeve threaded on the rotatable member having a disengageable driving connection with the pinion; and a member having a frictional driving connection with one of the said sleeve and pinion parts and a driving connection with the other of said parts whereby relative rotary movement between the pinion and the sleeve will cause the sleeve to move along its thread towards and away from the pinion to set and unset the driving connection between the sleeve and pinion.
19. A starter comprising a pinion adapted to be moved into and out of mesh with a gear of an engine to be started; a rotatable starter member axially movable and adapted to impart axial movement to the pinion to withdraw it from mesh; a sleeve threaded on the rotatable member having a disengageable driving connection with the pinion; and a member having a frictional driving connection with one of the said sleeve and pinion parts and a driving connection with the other of said parts whereby the last mentioned member when the sleeve overruns the pinion, will cause the sleeve to move along its thread to set the driving connection between the sleeve and pinion.
20. A starter comprising a pinion to be moved into and out of engagement with a gear of an engine to be started; a rotatable starter member axially movable and adapted to impart axial movement to the pinion to withdraw it from mesh; a sleeve threaded on the rotatable member having a disengageable driving connection with the pinion; and a member having a frictional driving connection with one of the said sleeve and pinion parts and a driving connection with the other of said parts whereby the member, when the pinion overruns the sleeve, will cause the sleeve to move along its thread to disengage the driving connection.
21. An engine starter including a longitudinally movable rotatable member; a pinion adapted to mesh with a gear of an engine; an intermediate driving member; a clutch between the pinion and intermediate driving member; camming provisions between the said two members adapted to permit relative longitudinal movement between said members and to cause the intermediate member to turn the pinion to clear its teeth if they should collide with the teeth of the gear; and a device having a driving connection with the intermediate driving member and operable by the pinion for effecting a separation of the clutch during such times as the pinion overruns the intermediate driving member and for effecting a driving engagement of the clutch when the speed of the pinion falls below that of the intermediate member.
22. An engine starter including a longitudinally movable rotatable member; a pinion adapted to mesh with a gear of an engine; an intermediate driving member having a slideable driving connection with the first named member; a clutch between the pinion and intermediate driving member; and a device having a slideable connection with the intermediate driving member, one of the said slideable connections including a curved spline, the device being operable by the pinion for moving the intermediate driving member along the curved spline away from the pinion to maintain a separation of the clutch during such times as the pinion overruns the intermediate driving member.
23. An engine starter including a longitudinally movable rotatable member; a pinion adapted to mesh with a gear of an engine; intermediate driving member having a slideable driving connection with the first named member; a clutch between the pinion and intermediate driving member; and a device for releasing the clutch having a slideable connection with the intermediate driving member, one of the said slideable connections including a curved spline; and means for establishing a drive connection between the device and pinion adapted to permit slippage therebetween whereby the device will turn the intermediate driving member along its curved spline connection and hold it as positioned until the relative speeds of the pinion and the first mentioned member have been reversed.
24. An engine starter including a longitudinally movable rotatable member; a pinion adapted to mesh with a gear of an engine; an intermediate driving member having a slideable driving connection with the first named member; a clutch between the pinion and intermediate driving member; a device for setting and unsetting the clutch having a slideable connection with the intermediate driving member, one of the said slideable connections including a curved spline; and means for retaining the device in frictional engagement with the pinion whereby relative rotary movement between the device and pinion will effect a separation of the clutch.

movement on the curved spline will result in the intermediate driving member being moved axially.

25. An engine starter including a longitudinally movable rotatable member; a pinion adapted to mesh with a gear of an engine; an intermediate driving member having a slideable driving connection with the first named member; a clutch between the pinion and intermediate driving member; and a device having a slideable connection with the intermediate driving member, one of the said slideable connections including a curved spline, the device being operable by the pinion for effecting a relative rotary movement on the curved spline to move the intermediate driving member axially and establish a driving engagement of the clutch when the rotary speed of the intermediate driving member exceeds that of the pinion.

26. An engine starter including a rotatable member; a pinion for meshing with a gear of an engine to be started; a clutch member adapted to form a drive connection between the pinion and the rotatable member and having a slideable connection with the latter; and a device having a drive connection with the pinion adapted to permit slippage between the device and pinion, the device having a slideable connection with the clutch member, one of the said slideable connections including a curved spline whereby relative rotary movement thereon will result in the clutch member being moved axially away from the pinion while the latter is overrunning the rotatable member.

27. An engine starter including a rotatable member; a pinion for meshing with a gear of an engine to be started; an intermediate driving member having a sliding driving connection with the rotatable member; a one-way clutch for forming a drive connection between the intermediate driving member and the pinion; and a device having a drive connection with the pinion adapted to permit slippage between the device and pinion, the device having a slideable driving connection with the clutch, one of the said slideable driving connections including a curved spline whereby rotary movement thereon will result in an axial movement of the intermediate driving member to separate the clutch while the pinion is overrunning the rotatable member.

28. An engine starter including a longitudinally movable rotatable member; a pinion adapted to mesh with a gear of an engine; an intermediate driving member having a slideable driving connection with the first named member; a clutch between the pinion and intermediate driving member; a device having a slideable connection with the intermediate driving member; one of the said slideable connections including a curved spline, the device being operable by the

pinion for moving the intermediate driving member away from the pinion to maintain a separation of the clutch during such times as the pinion overruns the intermediate driving member; and means for preventing more than a predetermined axial movement of the intermediate driving member when it is moved to disengage the clutch.

29. A starter comprising a pinion to be moved into and out of engagement with a gear of an engine to be started; a rotatable starter member axially movable and adapted to impart axial movement to the pinion to withdraw it from mesh; a sleeve threaded on the rotatable member having a disengagable driving connection with the pinion; a member having a frictional driving connection with one of the said sleeve and pinion parts and a driving connection with the other of said parts whereby the member, when the pinion overruns the sleeve, will cause the sleeve to move along its thread to disengage the driving connection; and means for limiting the said axial movement of the sleeve and for relieving the frictional engagement of the last mentioned member.

30. A starter comprising a pinion adapted to be moved into and out of mesh with a gear of an engine to be started; a flange carried by the pinion and provided with ratchet teeth; a rotatable starter member axially movable, one of the said flange and member parts being provided with a part adapted to limit the axial movement of the pinion relative to the member; and a sleeve threaded on the rotatable member and provided with ratchet teeth adapted to co-operate with the ratchet teeth on the flange to form a drive connection between the sleeve and pinion.

31. An engine starter including a longitudinally movable rotatable member; a pinion adapted to be moved endwise to mesh with a gear of an engine; a main clutch for forming a driving connection between the said member and pinion, the said clutch including a part threaded on the member for turning the pinion to clear its teeth in case they collide with the teeth of the gear; and an auxiliary clutch between the pinion and the said part for effecting and maintaining the setting of the main clutch until such time as the pinion overruns the rotatable member.

Signed at Toronto, Canada, this 18th day of May, 1928.
